UNITED STATES PATENT OFFICE.

MANUEL D. DOMINGUEZ, OF NEW ORLEANS, LOUISIANA, ASSIGNOR OF TEN PER CENT TO CHARLES A. DENIS, AND GEORGE SARPY, BOTH OF NEW ORLEANS, LOUISIANA.

WATER HEATER AND CONTROL SWITCH THEREFOR.

Application filed May 20, 1922. Serial No. 562,442.

To all whom it may concern:

Be it known that I, MANUEL D. DOMINGUEZ, a subject of Spain, residing at New Orleans, in the parish of Orleans and State 5 of Louisiana, have invented certain new and useful Improvements in Water Heaters and Control Switches Therefor, of which the following is a specification.

The invention relates to electric water 10 heaters, and has as an object the provision of an efficient heating system which shall be readily portable. A further object of the invention is the provision of a water heater having a thermal device to control the electric 15 circuit which heats the water. An illustrative embodiment of the invention is shown in the accompanying drawings, in which—

Fig. 1 is a plan view;

Fig. 2 is a side elevation of a heating unit;

Fig. 3 is a detail inverted side elevation of a heating coil with a portion of the casting removed;

Fig. 4 is a side elevation, partly in section, of the complete device upon a smaller scale than that of Fig. 3;

Fig. 5 is a plan view of the construction shown in Fig. 4;

Fig. 6 is a detail vertical section upon an enlarged scale of a control valve;

Fig. 7 is an inverted detail central vertical section of the thermal element and switch;

Fig. 8 is a transverse section on broken line 8—8 of Fig. 7.

The heating unit shown in Figs. 1 and 2 comprises a pair of insulating disks 1 and 2 formed of refractory material held in 40 separated position by means of a rod 3 and nuts 4, 5, 6 and 7. To hold the element in place for use, a bar having a depressed center and upwardly offset arms 8 and 9 is shown as secured to the disk 1 by means of 45 a nut 10. A similar bar placed at right angles to that already described is secured to the disk 2 by means of the nut 12. The off-setting of the arms 8 and 9 is unequal to allow for the longitudinal displacement 50 of the turns of the coil of the pipe with which they are to contact, due to its horizontal form, as indicated at the top of Fig. 3.

To make electrical contact with the resistance wires of the heater a pair of metal

strips 13—14 are attached to the disk 1 55 as by means of screws 15—16. The metal strips are shown as angular in form with the securing screws at the end of one wing and with a binding screw 17—18 at the angle of each. 60

A binding screw 19—20 is also shown at the end of the other wing, which is upturned for formation of a binding post. The connections to the source of energy are made by means of the binding screws 65 19—20.

The resistance elements shown comprise a series of three acting in parallel, the ends of each of the series being attached respectively by means of the screws 17 and 18. 70 The helices of which the resistance elements consist are passed alternately through holes in the disks 1 and 2, the elements of the individuals of the series being mounted in openings concentric with the others. To 75 prevent deflection of the longitudinally extending portions of the helices a flexible cord of incombustible material is threaded through each longitudinal extension and secured to the disks 1 and 2. The heat generated by the resistance wires is applied to the water by mounting the heating element, as already indicated, within a coil 25 of a pipe formed of a metal of high conductivity, as for instance copper, said coil having its 80 terminals 35—36 connected, one with the bottom of a reservoir 39 and the other projecting thereinto and having a pipe 40 extending toward the top of the reservoir. The coil 25 is shown as encased within a 85 casing 26 and the space outside of the coil within the casing may be packed full of heat insulating material 28, such as mineral wool. The casing is preferably formed of two halves which may be connected together 90 by means of perforated lugs 32, screws 33 being passed therethrough, and nuts 34 tightened on the screws for a secure attachment.

The terminal 36 of the coil is shown as 100 connected with a T having an outlet pipe 37 upon one branch thereof and supplied with a faucet 38 by means of which hot water may be drawn at will. The casing 26 is shown as provided with a projecting 105 portion 29 which is divided upon the line of division between the two halves of the casing. An opening is formed therein pro-

vided with an insulating button 30 for passage of the cord 31 supplying current to the heating unit.

To control the application of the heat 5 to the water in the reservoir 39 in an efficient manner the top of the pipe 40 is shown as provided with a special form of valve comprising a thimble 41 having an upwardly tapering frusto-conical nozzle, 10 and the end of the pipe 40 is castellated, as is shown at 42, Fig. 6.

A ball 43 of some material lighter than water, as cork or hollow hard rubber, or light metal is shown seated upon the top 15 of the castellations. When steam is formed in the coil 25 so as to provide a rush of water upwardly in pipe 40 after the nature of a percolator, the opening from the nozzle 41 will be closed by the ball 43 and the 20 steam will be forced to find an outlet backward through pipe 35, thus delivering the steam through the body of the water in the reservoir 39 to rapidly and effectually heat the mass of water therein.

25 Preferably elbows 47-48 are provided upon the reservoir 39 between which elbows a gauge glass 46 is mounted so that the level of water in the reservoir can be readily determined.

30 To control the temperature in the reservoir a thermal switch, shown in Figs. 7 and 8, is provided. The thermal actuation of this switch is controlled by means of an expansible fluid, such as air or gas, or 35 even a liquid which is sealed within a shell 49, passing through the lower wall of the reservoir 39, the joint where the element passes through the wall of the reservoir being sealed by means of a nut lock 81 and gasket 80 clamped against a ring 52, exterior of the casing. The ring 52 is shown as formed with a shoulder against which a concaved diaphragm 51 is pressed, a gasket 50 of compressible material being interposed to provide a gas-tight enclosure 45 for the contents of the shell 49. By the term "continuously acting" as used in the claims, applicant intends to refer to the fact that the current flows continuously in 50 the heating coil, except as controlled by the thermal switch, as long as the device is connected to a source of current, and is not affected by the presence of water in the heating coil 25.

55 The terminal 53 is shown secured to the ring 52 and insulated therefrom by means of washers 54-55, one of which passes through an opening in the terminal 53 so as to insulate the securing screw 56 from 60 the terminal. Integral with the terminal 53 there is an upstanding ear 57 having a lever 58 pivoted thereon by means of a pin 59. The lever 58 carries an upwardly off-set terminal through which an adjusting screw 61 is passed, insulated therefrom by

means of a washer 60, the body of the washer preferably passing through a perforation in the terminal so as to complete the insulation therefrom. An adjusting screw 62 is shown and a spring 63 anchored to the screw 61 and also to an ear 64 secured to the ring 52. The resistance to movement of the bar 58 can therefore be adjusted by turning the screw 62. To the center of the bar 58 a post 65 is shown as attached, having a button 66 secured upon its end, at least the tip of the button being formed of insulating material and standing close to the diaphragm when in its inwardly convex form.

70 A bar 67 is shown as projecting under bar 58 and as secured to and insulated from the ring 52, a binding post 68 being formed integral therewith to which post a wire 70 is shown as attached by means of a screw 69. The second wire of the cord 31 is shown as attached by a binding screw 74 to a post 72 integral with a second terminal 71. The terminals 53 and 71 are adapted to make contact with a plug 79 mounted upon a current supply cord 80 having an extension plug 81 at its end which may be screwed into any available electric light socket. A cover 75 may be secured over the switch and the terminals 53, 71 by screw 76 taking into 75 the edges of the ring 52.

80 Preferably a cover 44 is shown for supplying the interior of the casing 39 with water, and the reservoir may be suspended in any desired location by means of ears 100 45. The casing 39 is adapted to be supported from the casing 39 by means of the pipes 35-36.

85 The current will be supplied to the heating element at any time that the temperature of the water in the reservoir 39 falls below that for which the thermal switch is set. When merely steam passes upward through the pipe 40 it will be allowed to readily escape through the castellation 42, but when steam is generated so rapidly as to provide a rush of water up the pipe the hot water and steam will be forced backward through the pipe 35 so as to very rapidly 90 heat the water in the casing 39. However when water is drawn from the faucet 38, since the valve 41 will be substantially at all times above the level of the water in the reservoir, the water flowing from the faucet will come through the heating coil and will therefore be the maximum temperature at which the water will be found in the system. There is therefore provided an efficient hot water supply system which is 95 automatic in operation and which is readily portable, being not dependable upon a pressure water supply system for its action. The reservoir 39 may be made of any desired size and may be heat insulated in any desirable manner.

Minor changes may be made in the physical embodiment of the invention without departing from its spirit.

I claim:

- 5 1. A water heating system comprising a reservoir, a continuously acting heater connected to said reservoir and means to reverse the circulation of water through said heater upon the generation of steam pressure whereby water and steam from the heater will be delivered to the bottom of the body of water in the reservoir.
- 10 2. A water heating system comprising a reservoir, a heating coil having a connection adjacent the body of said reservoir and a second connection opening adjacent to the top of the interior of said reservoir, means to reverse the natural heating circulation of water through said heater.
- 15 3. A water heating system comprising in combination, a reservoir, a heating coil hav-

ing one end connected to the bottom of said reservoir and the other end extending within the reservoir and terminating in a stand pipe opening adjacent the top of the interior of the reservoir, a valve upon said stand pipe adapted to allow free escape of steam and air but to check the escape of water, whereby pressure of steam must escape from the heater through the lower connection to the reservoir.

4. A heater comprising in combination a helical coil of pipe, spaced disks within said coil, arms secured to said disks having upwardly off-set portions, the off-setting of the arms being unequal to coact with the opposite sides of the pipe helix, the arms at the top and bottom of the heater unit being at 90° to each other, and resistance elements mounted between said disks.

MANUEL D. DOMINGUEZ.
